UNITED STATES PATENT OFFICE

2,526,383

WAVE GUIDE MODE CONVERTER

Edwin H. Meier, Tulsa, Okla., assignor to General
Electric Company, a corporation of New York

Application January 23, 1948, Serial No. 4,022

3 Claims. (Cl. 178—44)

1

My invention relates to a wave guide structure and, more particularly, to a wave guide structure for converting from a rectangular wave guide to a circular wave guide.

In most systems which employ wave guides to channel the radio frequency energy to and from an antenna, it is often necessary to change the position of the antenna with respect to the input guide. In order to obtain this freedom, rotating joints are necessary. That is, there must be joints in the radio frequency system where the guide on one side of the joint must rotate with respect to the guide on the other side of the joint about the longitudinal axis of the guides. In order that rotation may take place without disturbing the propagation of the radio frequency power across the point of rotation, both the guide and the mode of propagation must have circular symmetry about the longitudinal axis of the guide in this region. However, most systems employ a rectangular guide propagating the TE₀₁ mode. This is especially true where it is necessary to transmit over any appreciable distance. Therefore, some method of conversion from the rectangular TE₀₁ mode to a symmetrical mode in the cylindrical guide is necessary.

It is an object of my invention to convert from a rectangular to a cylindrical wave guide without loss of power. A further object of my invention is to obtain circular polarization. A still further object of my invention is to provide a rotating joint that is simple and has small losses.

The features of my invention which I believe to be novel, are set forth with particularity in the appended claims. My invention itself, however, together with further objects and advantages thereof, may best be understood by reference to the following description taken in conjunction with the accompanying drawing in which Fig. 1 is a block diagram of a typical rotating coupling section, Fig. 2 is a side view of a wave guide structure embodying my invention, Fig. 3 is an end view of the structure shown in Fig. 2 and Figs. 4 and 5 are cross-sectional views through the guide sections in Fig. 2 conventionally showing the electrical and magnetic vectors for waves therein.

For a better understanding of my invention, now refer to a typical rotating coupling section as shown in Fig. 1 in which I have shown a rectangular input guide 1, and a rectangular output guide 8 which may rotate with respect to the guide 1 about the axis AA. The rectangular guides 1 and 8 are connected to the conversion joints 2 and 7 respectively. The two cylindrical guides 3 and 6 extend outwardly from the conversion joints 2 and 7 and terminate in the choke joints 4 and 5. The conversion joint 2 is used to convert from the TE₀₁ mode in the rectangular

2

guide to a suitable mode in the cylindrical guide. The conversion joint 7 which may be identical in construction to the joint 2, is used to convert from the mode in guide 6 to the TE₀₁ mode in the rectangular guide 3.

At present two types of rotating sections are commonly used. The first utilizes the circular TM₀₁ mode for the cylindrical guides 3 and 6 with 2 and 7 being conversion joints for converting the TE₀₁ wave propagated in the rectangular guide to this circular mode in the cylindrical guide. A cylindrical guide which will propagate the symmetrical TM₀₁ mode will necessarily propagate the circular TE₁₁ mode which is non-symmetrical about the longitudinal axis of the guide and complicates the design and adjustment of the conversion joints, causing the distance *d* in Fig. 1 to have critical length which it is highly desirable to avoid. The cross section 20 of the cylindrical guide propagating the TM₀₁ mode in this case must be relatively large compared to that of the rectangular guide which causes the conversion joint to be correspondingly large.

25 A second type of rotating section now commonly used as the symmetrical portions 3 and 6 comprises sections of coaxial transmission lines. In this type, the conversion joints 2 and 7 comprise means for converting from the TE₀₁ wave of the rectangular guides to the transverse electromagnetic waves propagated in the section of coaxial transmission lines. This type of converter requires a rotating joint in a coaxial line.

In a preferred embodiment of my invention, 35 the rotating section is built primarily about a conversion joint which converts the TE₀₁ mode in a rectangular wave guide to a circular polarized TE₁₁ mode in a cylindrical guide. These conversion joints, as illustrated in Fig. 2, are used 40 as the elements 2 and 7 in Fig. 1 with elements 3 and 6 being circular wave guides of such dimensions that they propagate waves of the TE₁₁ mode. The choke rotating joints as shown at 4 and 5 comprise conventional chokes for this type of 45 guide and mode.

Referring now to Fig. 2, I have shown a rectangular wave guide section 10 having an inductive diaphragm 11 disposed within the section intermediate its ends and having its upper end 50 joining with the circular wave guide section 12. Across a stub end of the guide 12 is connected a short-circuiting plate 13. Attached to the plate 13 and extending into the guide 12, is a web 14 which is mounted at a 45 degree angle with 55 respect to the longitudinal axis of the rectangular guide, as may be best seen in Fig. 3.

The rectangular wave guide 10 is secured to the side of the cylinder guide 12 with the broad face of the rectangular guide parallel to the axis

of the cylinder guide. An opening is formed in the wall of the cylinder guide having the same dimensions as the cross section of the end of the rectangular guide. To one side of this opening the guide extends towards the rotating joint and the converted power is propagated along this leg. To the other side of the opening, the circular guide is short-circuited by plate 13 and the metallic web 14 which is supported directly in front of the plate 13. The web 14 and plate 13 produce two equal electrical vectors, one of which is parallel to the web and the other perpendicular to it. The vector parallel to the web is short-circuited at the leading edge of the web. However, the perpendicular vector is reflected by plate 13 at the end of the stub. If the web 14 is electrically $\frac{1}{8}$ guide wave length in length, the two equal vectors are perpendicular and have a phase difference of 90 degrees which results in a circular polarized wave being propagated along the cylindrical guide. By using a similar structure at the other end of the system the wave can be fed back into the rectangular guide exactly the same as the one originally supplied. This permits the circular section to be mechanically rotated without affecting the energy supplied to the output line.

The radio frequency energy is supplied from the rectangular guide into the cylindrical guide with its polarization at an angle of 45 degrees with the plane of the web. This causes two components of the TE₁₁ mode polarized at right angles to one another to be propagated toward the rotating joint. If these two components are equal and 90 degrees out of time phase, the desired circular polarization is obtained. These conditions are obtained when the distance *a* in Fig. 2 is equal to $\frac{1}{8}$ guide wave length and the distance *b* is equal approximately to $\frac{1}{6}$ guide wave length. Conventional representations of the electrical and magnetic vectors in the guide sections 10 and 12 are shown in Figs. 4 and 5, for the TE₀₁ and TE₁₁ modes respectively.

The inductive diaphragm 11 in the rectangular guide near the conversion joint is necessary to match the discontinuity caused by the conversion joint.

With the components of this type of rotating section, power may be supplied to either of the rectangular guides and fed from the other rectangular guide into a matched load without any mismatch in the system regardless of the relative position of the two rectangular guides. The chief advantages of my invention are the simplicity of construction, small physical size, absence of excessive voltage gradients, and non-critical length between a pair of conversion joints.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. In a wave guide structure, a rectangular section, a circular section, said rectangular section having its major transverse axis parallel to the longitudinal axis of said circular section and its longitudinal axis substantially perpendicular to the longitudinal axis of said circular section, said circular section having a stub end extending

at least $\frac{1}{2}$ electrical wave length beyond the adjacent wall of said rectangular guide, said stub end terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode when passing from said rectangular to said circular section, or from the TE₁₁ mode to the TE₀₁ mode when passing in the reverse direction.

5 2. In a wave guide structure, a rectangular section, a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

10 3. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

15 4. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

20 5. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

25 6. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

30 7. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

35 8. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

40 9. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

45 10. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode.

50 11. In a wave guide system, a pair of substantially similar relative rotatable wave guide sections, each section having a rectangular section and a circular section, said rectangular section having its major transverse axis parallel to the longitudinal axis of said circular section and its longitudinal axis substantially perpendicular to the longitudinal axis of said circular section, said circular section having a stub end extending at least $\frac{1}{2}$ electrical wave length beyond the adjacent wall of said rectangular guide and terminated by a shorting member, a web member adjacent said shorting member and extending along the longitudinal axis of said circular section for substantially $\frac{1}{8}$ electrical wave length and forming an acute angle with the longitudinal axis of said rectangular section, the lengths of said stub and web members and said angle being selected to cause guided waves to be converted from the TE₀₁ mode to the TE₁₁ mode, and means for electrically connecting said circular sections so that they are relatively rotatable, transfer of energy between said sections being substantially independent of the distance between said rectangular sections.
